US0D1113803S

(12) **United States Design Patent** (10) **Patent No.:** **US D1,113,803 S**
(45) **Date of Patent:** **** Feb. 17, 2026**

(54) **HEADPHONE EAR CUPS, CUSHIONS, AND SUPPORTS**

(71) Applicant: **Dyson Technology Limited**,
Malmesbury (GB)

(72) Inventors: **Simon Brian McNamee**, Bristol (GB);
Howard Shi-How Cheng, Bristol (GB);
Philip Stephen Douglas, Bristol (GB);
Damian Calvo Tome, A Coruña (ES);
Chun Hei Poon, Singapore (SG)

(73) Assignee: **Dyson Technology Limited**,
Malmesbury (GB)

(**) Term: **15 Years**

(21) Appl. No.: **29/954,707**

(22) Filed: **Jul. 29, 2024**

(30) **Foreign Application Priority Data**

Jan. 31, 2024 (GB) 6343518
Jan. 31, 2024 (GB) 6343524

(51) **LOC (15) Cl.** **14-01**

(52) **U.S. Cl.**

USPC **D14/205**

(58) **Field of Classification Search**

(57) **CLAIM**

The ornamental design for headphone ear cups, cushions, and supports as shown and described.

DESCRIPTION

FIG. 1 is a perspective view of headphone ear cups, cushions, and supports showing our new design.

FIG. 2 is a front view thereof.

FIG. 3 is a rear view thereof.

FIG. 4 is a right side view thereof.

FIG. 5 is a left side view thereof.

FIG. 6 is a top view thereof.

FIG. 7 is a bottom view thereof.

FIG. 8 is a perspective view of headphone ear cups, cushions, and supports showing our new design.

FIG. 9 is a front view thereof.

FIG. 10 is a rear view thereof.

FIG. 11 is a right side view thereof.

FIG. 12 is a left side view thereof.

FIG. 13 is a top view thereof; and,

FIG. 14 is a bottom view thereof.

The broken lines show portions of the design that form no part of the claimed design.

1 Claim, 14 Drawing Sheets
